UNITED STATES PATENT OFFICE

JAMES W. INGLETON, OF ASTORIA, OREGON

EXPLOSIVE-FUEL-MIXTURE GENERATOR FOR HYDROCARBON ENGINES

Application filed August 18, 1925. Serial No. 50,962.

The invention relates to new and useful improvements in a vaporizer for hydrocarbon engines.

An object of the invention is to provide a vaporizer wherein steam is thoroughly intermixed with vaporized or gasified hydrocarbon oil and air prior to the supplying of the mixture to the combustion chamber of the cylinder.

10 A further object of the invention is to provide a vaporizer of the above type wherein the hydrocarbon oil is vaporized or gasified by heat, after which it is thoroughly mixed with air, and wherein said vaporized or gasified oil and air is supplied with steam before the mixture is supplied to the combustion chamber.

15 A still further object of the invention is to provide a vaporizer of the above type, wherein in water is supplied to the vaporizer which vaporizes or gasifies the oil, so that said water will be generated into steam and the steam thoroughly intermixed with the vaporized hydrocarbon oil.

20 A still further object of the invention is to provide a vaporizer of the above type, wherein in the vaporizer is located adjacent the exhaust manifold and so that the vaporizing chamber will be heated by the exhaust gases.

25 A still further object of the invention is to provide a vaporizer consisting of a series of chambers which are interconnected so that the hydrocarbon oil to be vaporized may be fed to certain of said chambers, and the vapor generated during the heating of said chamber passed into another chamber where it is further heated and vaporized.

30 A still further object of the invention is to provide a vaporizer of the above type, wherein in said chambers are so positioned that any heavy fuel particles collecting on the walls of the vaporizing chambers will flow along the walls of the chamber to a point where said heavy particles are further subjected to a vaporizing heat so as to insure a more efficient vaporizing or gasifying of the hydrocarbon oil.

35 These and other objects will in part be obvious and will in part be hereinafter more fully disclosed.

In the drawings which show by way of illustration one embodiment of the invention—

Figure 1 is a front view showing my invention applied to a hydrocarbon engine;

Fig. 2 is a view showing a portion of one of the cylinders diagrammatically and the arrangement of my improved devices relative thereto;

Fig. 3 is a vertical sectional view through my improved generator for vaporizing or gasifying the hydrocarbon oil and for supplying steam to the vaporized or gasified oil;

Fig. 4 is a sectional view on the line 4—4 of Fig. 3, and

Fig. 5 is a sectional view on the line 5—5 of Fig. 4.

The invention in its broadest aspects is directed to a vaporizer for hydrocarbon engines, and includes a generating chamber wherein the hydrocarbon oil is subjected to heat so that it will be vaporized or gasified. It is believed that these terms are synonymous, and therefore, the term "vaporized" as applied to the effect upon the hydrocarbon oil will be used in its broadest aspect to cover either a vapor form of fuel or gas form of fuel. Likewise, the term "vaporizer" will be used in its broadest sense. After the oil has been vaporized, it is passed through an air mixer where air is thoroughly mixed therewith, and is thence supplied to the combustion chamber or chambers of the engine. Means is provided also for supplying water to the generating chamber so that steam will be thoroughly mixed with the vaporized oil and the supply of water can be regulated so that the amount of steam mixed with the vaporized oil can be varied. The oil supply can likewise be varied. The purpose of this steam in the vaporized oil is to prevent the formation of carbon deposits on the wall of the generator, and in fact, throughout the system in which it is used, including the combustion chamber of the engine. The steam is thoroughly mixed with the vaporized fuel oil and the air subsequent to passing into the combustion chamber of the engine. This steam in the combustion chamber not only tends to prevent the formation of carbon deposits, but also prevents premature firing

80

under compression, and the subsequent knocking which results therefrom. This is accomplished by regulating the amount of water supplied to the generating chamber.

5 The vaporizer includes a series of generating chambers which are connected, and all of which are located in the heating medium for the generator. The hydrocarbon oil to be vaporized is fed into the lower chamber 10 of the generator and as it is vaporized, it passes into the upper chamber and thence out through to the air mixer. The purpose of having the series of chambers is to extend the area through which vaporization is accomplished. These chambers are inclined and so connected that any oil not thoroughly vaporized collecting on the bottom of the upper chamber will flow back into the lower chamber and again pass through the cycle 15 of heating for vaporization.

Referring more in detail to the drawings, my improved generator consists of an outer casing 1 which is preferably provided with flanges 2 and 3. As illustrated in the drawings, the flange 3 of this generator is connected to the exhaust manifold 4 of the engine, and all the exhaust gases pass into and through this casing 1. The upper flange 2 is connected to a similar flange on the exhaust pipe 5. Located in the casing 1 as illustrated in the drawings, are three generating chambers 6, 7 and 8. The chamber 6 is connected to the chamber 8 by means of a short pipe 9, and the chamber 7 is connected 20 to the chamber 8 by means of a short pipe 10. The casing 1 is provided with a compartment 6^a, for the chamber 6; a compartment 7^a for the chamber 7, and a compartment 8^a for the chamber 8. These compartments are formed 25 integral with the walls of the casing and are located within the casing 1. The chambers are inserted in these compartments, and each chamber is secured in its respective compartment by a cap plate 11 and suitable bolts 12. Each chamber has a flanged head 13, which 30 rests in a recess or seat formed in the outer wall of the casing 1 adjacent the outer end of its respective compartment. The cap plate 11 is not only secured to the chamber, but 35 also operates to secure the chamber in the compartment. It is understood that the pipes 9 and 10 pass through the walls of the compartments and are in line with openings 40 the walls of the generating chambers.

50 Located in the casing 1 is a series of baffle plates indicated at 14, 14. These baffle plates are shaped to correspond to the casing in cross section at the intermediate portion thereof, and are welded to the wall of the casing, so that they are rigidly supported therein. Each baffle plate is provided with an opening therethrough which fits over the portions 55 of the casing forming the compartments 6^a, 7^a and 8^a. These baffle plates are spaced from each other and are welded to the outer walls

of these compartments. There is also a partition plate 15 welded to the inner wall of the casing 1 and extending from a point 16 adjacent the flange 3 to a point 17 adjacent one of the baffle plates. There is a similar partition plate 18 extending from a point 19 adjacent the upper flange 2 to a point 20 adjacent the upper edge of one of the baffle plates. These partition plates are so located that the exhaust gases will pass up between certain of the baffle plates at the left as shown in Fig. 3, then down between certain of the baffle plates in the center of the generator, and finally up between the baffle plates at the extreme right in this figure, and then out through the opening in the flange 2 into the exhaust pipe 5. The purpose of these partitions and baffle plates is to cause the exhaust gases to pass in and about the portions of the casing forming the compartments and thus cause a very efficient heating of the generating chambers.

90 The hydrocarbon oil to be vaporized, according to the present embodiment of the invention, is fed into both the generating chamber 6 and into the generating chamber 7. These hydrocarbon oil supply devices are similar in construction, and a description of one will answer for both. Connected to the cap plate 11 of one of the lower compartments is a fuel nozzle or supply pipe 22. There is a similar fuel nozzle or supply pipe 22^a for the other lower compartment. There is likewise a supply nozzle 21 connected to this cap plate 11 for supplying water to this vaporizing chamber 6, and a similar nozzle 21^a for supplying water to the vaporizing chamber 7. All of these nozzles are similar in construction, and one of them is shown in detail in Fig. 5. The nozzle consists of a casing or pipe 23 having a discharge opening 24 in the inner end thereof. Said casing has an enlargement 25 which bears against the cap plate 11 and may be welded thereto. Located in this casing or pipe 23 is a needle valve 26 provided with a tapered end 27 which is adapted to enter the discharge opening 24. The outer end of the needle valve 26 passes through a suitable packing gland 28 and on the outer end of the needle valve stem there is secured a plate 29 against which a spring 30 presses. This spring operating upon the plate forces the needle valve into the opening 24 and closes the same. Connected with the casing or pipe 23 is a supply pipe 31 through which the oil or water passes into the pipe or casing 23 and out through the discharge opening 24 when it is open. Both the oil and water are fed to the generator by pumps so that the oil and water is under pressure. The pressure of the oil or water against the tapered end 27 of the needle valve will force the needle valve outwardly, or to the right as viewed in Fig. 5, against the tension of the spring 30, thus opening the port 24, so that the fluid will pass 100

into the generating chamber. The extent to which this needle valve may be opened is determined by a stop screw 32, which is located in a cap 33 attached to the casing 25 and housing the spring 30. This stop screw is provided with a suitable head 34 accessible to the operator so that it may be readily adjusted, and a set nut 35 is used for the purpose of locking it in set or adjusted position. It will be understood, of course, that when the pressure of the feed pumps is sufficiently high for successful operation of the engine, this needle valve is moved to open position, and will remain open unless for some reason the pressure of the pump or the fuel supply drops to such a point that the spring will close the valve. The extent to which it is opened, depends, as above noted, upon the position of the stop screw 32.

The oil fed into the lower vaporizing compartment will be vaporized by coming in contact with the heated walls of the generating chamber, and the vaporized oil will pass through either the pipe 9 or 10 into the upper generating chamber 8. The upper generating chamber 8 is connected to a pipe 36 and this pipe 36 as shown in Fig. 2 of the drawings, is connected to an air mixer 37. This air mixer is, in construction, of the type shown in my companion application Serial No. 50,961, filed of even date herewith, and detail description thereof is not thought necessary. This air mixer has a suitable intake valve yieldingly closed and subject to the suction of the engine. The vaporized oil passing through the pipe 36 into the air mixing chamber will be thoroughly mixed with air and will then pass to the manifold of the engine. A suitable valve is provided so that the vaporized oil mixture just referred to may be cut off and the engine connected to an ordinary gasoline carburetor for starting. Suitable means indicated at 38 is also provided for collecting the heavy condensing oil vapors in the air mixing chamber and leading the same back to the supply.

The generating chambers 6 and 7 are inclined slightly downwardly from the right-hand end as viewed in Fig. 3, to the rear or left-hand end thereof, and the purpose of this inclination of these generating chambers is to cause any oil collecting in the bottom of the chamber to flow to the farther end thereof, so that it will be subjected to a vaporizing heat for the full length of time available in the generator. The vaporized oil passes from these lower generators through the pipes 9 and 10 to the upper generator and thence along the upper generator and out through the pipe 36. This upper generator is inclined from the left-hand end to the right-hand end thereof, as indicated in Fig. 3 of the drawings, so that any heavy oil accumulating or collecting on the bottom of the upper generating chamber will flow along

said lower wall and back through the pipes 9 and 10 into the lower generators, and along the bottom walls of the lower generators to the rear ends thereof, so that said heavy oil will be again subjected to the heat of the exhaust gases and caused to vaporize and pass on into the upper chamber. Thus it is that the hydrocarbon oil will be vaporized more efficiently, as the heavy non-vaporized oil running back will continue to cycle in the generator until it is thoroughly vaporized. The water passing into the generators, will, of course, be at once turned into steam, and this steam will be thoroughly mixed with the vaporized hydrocarbon oil. The presence of the steam in the vaporizing chambers will prevent the formation of carbon deposits in said chamber, and thus always keep the walls of said chambers clean and thereby the efficiency of vaporization is very greatly increased. These inner generating chambers are all removable from the casing with very little trouble so that they may be thoroughly cleaned. The walls of the generating chambers are straight, and when the cap plates are removed, they can be readily scraped. The use of the steam, however, to a great extent avoids the necessity of the cleaning of these generators.

The steam passes along with the vaporized oil and is present in the vaporized oil before the air is mixed therewith, and therefore, the steam is thoroughly mixed with the air and vaporized oil as the explosive mixture passes into the engine cylinders. The presence of the steam in the fuel mixture likewise prevents the formation of carbon deposits on the walls of the cylinder and the head of the piston. The steam in the combustion chamber, however, performs another very important function. It prevents premature firing and knocking. If a knocking occurs in the engine, it is unquestionably due to premature firing, the amount of water is increased by manipulating the valve controlling the water supply. This increases the amount of steam present in the combustible fuel, and will result in diluting or in modifying the character of the combustible fuel so as to prevent the same from exploding prematurely due to the compression in the cylinder.

While I have shown the steam introduced into the fuel mixture as generated in the vaporizing chamber for the hydrocarbon oil, it will be understood that steam may be otherwise intermixed with the vaporized oil, but it is essential, however, to the present invention, that this mixing of the steam with the vaporized oil occurs before the vaporized oil reaches the combustion chamber, and it is preferable to mix the steam with the vaporized oil in the vaporizing chamber, as it prevents the formation of carbon deposits therein, and thus greatly increases the efficiency of vaporization in the generating chambers.

While I have shown the vaporizer as located in a connection between the exhaust pipe and the exhaust manifold, it will be understood that this vaporizer may be placed in the engine cylinder as shown in my prior application, Serial No. 49,527, filed August 11, 1925. Likewise, this vaporizer may be entirely separate from the exhaust manifold or the engine cylinder, and the exhaust gases 10 passed into said vaporizer for heating the generating chambers therein, as shown for example in my copending application above referred to.

It is obvious that minor changes in the 15 details of construction and the arrangement of the parts may be made without departing from the spirit of the invention as set forth in the appended claims.

Having thus described the invention, what 20 I claim as new and desire to secure by Letters-Patent, is—

1. A vaporizer for hydrocarbon engines comprising a casing, means for passing the exhaust gases from the engine through said 25 casing, a plurality of generating chambers located in said casing and connected one to another, means for supplying oil to one of said chambers whereby the oil fed thereto will be vaporized and caused to pass into another 30 chamber, means for leading the vaporized oil from said last named chamber out through the casing into an air mixer, means for regulating the supply of oil to said chambers, means for supplying water to the chambers 35 whereby steam is generated and intermixed with the vaporized oil, and means for regulating the amount of water supplied to the chambers, the chamber receiving the vaporized oil being higher than the chamber receiving the 40 oil to be vaporized and inclined so that any oil collecting on the bottom of the higher chamber will drain back into the chamber receiving the oil from the supply and be subjected to further vaporizing heat.

2. A vaporizer for hydrocarbon engines comprising a casing having an opening in the bottom thereof whereby the exhaust gases from the engine may be caused to pass into said casing, said casing having an opening 50 in the upper end thereof through which the exhaust gases pass from the casing, said casing having inwardly projecting portions forming spaced compartments located within the casing, a vaporizing chamber removably secured in each compartment, baffle plates located in said casing and forming a connection between the outer walls of said compartments and the inner walls of said casing whereby the exhaust gases are caused to flow 55 in a circuitous path about said compartments, means for supplying one of said vaporizing chambers with a hydrocarbon oil, means for connecting said vaporizing chambers whereby the vaporized oil will pass into another chamber and means connected to the 60

last named chamber and extending through said casing for conducting the vaporized oil to an air mixer.

3. A vaporizer for hydrocarbon engines comprising a casing having an opening in the bottom thereof whereby the exhaust gases from the engine may be caused to pass into said casing, said casing having an opening in the upper end thereof through which the exhaust gases pass from the casing, said casing having inwardly projecting portions forming spaced compartments located within the casing, a vaporizing chamber removably secured in each compartment, baffle plates located in said casing and forming a connection between the outer walls of said compartments and the inner walls of said casing whereby the exhaust gases are caused to flow in a circuitous path about said compartments, means for supplying one of said vaporizing chambers with a hydrocarbon oil, means for connecting said vaporizing chambers whereby the vaporized oil will pass into another chamber, means connected to the last named chamber and extending through said casing for conducting the vaporized oil to an air mixer, and means for supplying water to said vaporizing chamber and for regulating the supply of water thereto.

In testimony whereof, I affix my signature. 95
JAMES WM. INGLETON.
